Samuel Hill and W. B. Cline of Philadelphia, Pa.
Letters Patent No. 253. Dated Dec 4, 1849.

The schedule referred to in these Letters Patent and making part of the same.

To all whom it may concern:

Be it known that we Samuel Hill and W. B. Cline of the County of Philadelphia, State of Pennsylvania have invented or produced a design of a new Cast Iron front, Bottom, side, and top, to be used together to form a design for a new Cannon Stove, and we hereby declare that the following is a full and exact description.

Figure 1 front, Figure 2 Bottom, Figure 3 side, Figure 4 Top. The annexed drawing is a correct representation of the same.

Your petitioners claim to be the original and first inventors or producers of the combination of the ornamental figures constituting one design as herein set forth.
